[57] **CLAIM**

The ornamental design for lens for an auxiliary vehicle signal, as shown and described.

DESCRIPTION

FIG. 1 is a plan view of the present invention;
FIG. 2 is a front view of the present invention;
FIG. 3 is a bottom view of the present invention;
FIG. 4 is a left side view of the present invention;
FIG. 5 is a right side view of the present invention;
FIG. 6 is a rear view of the present invention;
FIG. 7 is a perspective view of the present invention; and,
FIG. 8 is a perspective view of the present invention on a reduced scale, the truck being shown in broken lines for illustrative purposes only, and forming no part of the claimed design.

FIG. 1**FIG. 2****FIG. 3**
